UNITED STATES PATENT OFFICE.

FELIX PIRRUNG AND GEORGE F. PIRRUNG, OF CHICAGO, ILLINOIS.

DUST-MOP.

1,091,700.

Specification of Letters Patent. Patented Mar. 31, 1914.

Application filed July 31, 1913. Serial No. 782,187

To all whom it may concern:

Be it known that we, FELIX PIRRUNG and GEORGE F. PIRRUNG, citizens of the United States, residing at Chicago, in the county 5 of Cook and State of Illinois, have invented a certain new and useful Improvement in Dust-Mops, of which the following is a specification.

Our invention relates to mops for oiling 10 floors and for similar purposes, and the objects of the invention are first, to provide simple and efficient means for detachably attaching the "cloth"; second, to provide means for containing and evenly distributing 15 the oil to the yarn of the cloth; third, to provide convenient means for introducing the oil into the reservoir; fourth, to provide convenient means for detachably attaching the handle to stand at different angles 20 relatively to the body of the device; and fifth, to provide certain details of construction which will be hereinafter more particularly described and claimed.

We accomplish our objects by the construction shown in which—

Figure 1 is a perspective view of a mop embodying our invention. Fig. 2 is a vertical central section taken on the line 2—2 of Fig. 1. Fig. 3 is a perspective of the handle block. Fig. 4 is a sectional view on the line 4—4, Fig. 3. Fig. 5 is a plan view of the parts shown in Fig. 6. Fig. 6 is a perspective of the base which supports the cloth ring and serves to contain and distribute the oil to the cloth. Fig. 7 is a plan section on the line 7—7, Fig. 2. Fig. 8 is a sectional detail on the line 8—8, Fig. 6. Fig. 9 is a bottom plan view of the cup and associated parts, the view being taken on the line 9—9, Fig. 2. Fig. 10 is a vertical sectional view showing on an increased scale the parts shown at the center of Fig. 2.

Similar numerals refer to similar parts throughout the several views.

The so called "cloth" of the mop consists 45 of an annular body 1 from which the yarn or fabric 2 is suspended. The particular construction of the cloth is not an essential feature but by preference the cloth is formed 50 by stitching cloth over the looped strands

of the yarn. The ends of the body are brought together to form a ring by a strap 3 and buckle 4.

When assembled, the cloth is supported upon a base having in general a circular outline and provided with upstanding fingers 5 against which the ring or body of the cloth rests. Spouts 6 project radially from the base and serve both to support the mop body and to convey oil to the yarn strands from the oil reservoir formed within the base. Said spouts are present in considerable number and perform still another function; to-wit, they hold the strands of yarn against lateral displacement. Consequently 65 the strands when once evenly distributed are held so. The form of the reservoir may be varied, but according to the preferred construction there is an annular duct 7 bordered on the inside by the upstanding flange 8 and on the outside by the upstanding flange 9. This duct is fed by radial ducts 10 leading from a central receptacle 11.

Rising from the center of the base is a threaded post 12 upon which screws the internally threaded boss 13 of the block 14, shown in perspective in Fig. 3. The block is provided with flanges 15 for retaining the nut 16 by which the mop handle 17 is attached to said block. A hanger bolt 18 projecting from the lower end of the handle passes through the slot 19 lying between the flanges 15 and thus said flanges may be clamped between the nut and the end of the handle to hold the handle to the block. In 85 the design here shown, different portions of the flanges lie at different angles so that by fastening the handle at different points the angle which the handle assumes may be varied.

A cup 20 rests upon the annular wall of the receptacle 11 and is held there by screwing the block 14 down upon it. This cup is dished to receive oil and has an annular peripheral flange 20^a which projects over a 95 portion of the ring-like body of the mop cloth. Preferably the flange curves down at the edges to contact the top of the body and to impart a finished appearance to the device. In order to permit oil to flow from 100

the cup 20 past the block 14 down into the central receptacle 11, notches 14^a are formed in the side of the block, as best shown in Fig. 3. Cup 20 is centrally apertured, the 5 diameter of the aperture being greater than the width, of the central cross bar of the block 14, hence openings 20^a 20^b for the downward passage of oil are formed between the sides of the bar and the edges 10 of the aperture as best shown in Figs. 2, 9 and 10.

Preparatory to use, the parts are assembled as shown in Fig. 2. The block 14 holds the cup down to its seat and this in turn 15 holds the mop cloth down on the spouts 6. The handle 17 is then fastened at any angle desired. Oil is then introduced by pouring it into cup 20 whence it runs through the notches 14^a down into the receptacles and 20 ducts provided for it in the base. In passing out through the spouts 6 the oil is conducted to the very heart of the mop—that is, the yarn which is to do the oiling of the floors, etc. Thus there is an even distribution 25 of oil and yet the ends of the spouts are hidden and they are buried sufficiently to prevent their marring base boards or furniture. As the annular body of the cloth projects beyond the edge of the cup 20, it prevents the cup from striking and marring external 30 objects.

Having thus described our invention what we claim as new and desire to secure by Letters Patent, is:

35 1. In a mop, the combination with a cloth having an annular body, of a base provided with radial extensions for supporting the body of the cloth.

2. In a mop, the combination with a cloth

40 having an annular body, of a base having outwardly extending spouts supporting the body of the cloth and adapted to convey oil thereto.

3. In a mop, the combination with a cloth

45 having an annular body, of a base having upstanding fingers arranged in a circle against which the sides of the body of the cloth may rest, and radial projections formed at the bottom of the base for sup-

50 porting the body of the cloth.

4. In combination, a mop cloth, a base

55 having upstanding members arranged in a circle, fastening means for holding the body of the cloth in contact with said upstanding

members, and radial projections near the bottom of the base for supporting the body of the cloth.

5. In a mop, the combination of a base

60 having upstanding and also radially pro-

jecting members; a mop cloth having an

elongated body and strands suspended

therefrom, means for holding the body of

the mop in contact with said upstanding

and radially projecting members, and ducts in said base for conveying oil into the 65 strands of the mop.

6. In a mop, the combination of a base having upstanding members arranged in a circle near the periphery of the base, spouts extending outward therefrom, a receptacle 70 formed in said base, a mop cloth having an elongated body, means for holding said body in annular arrangement adjacent to the upstanding members on the base, a receptacle for oil in said base and ducts leading from 75 the receptacle to said spouts for conveying oil to the mop.

7. In a mop, the combination of an annular base, a mop having an annular body seating upon said base, a cup overlying a 80 portion of the body of the mop for holding the latter down in position, means for securing the cup to the base, and an oil duct leading from the cup to that portion of the base whereon the mop body seats. 85

8. In combination, a base for supporting the body of a mop, a cup seating upon said base and adapted to contain oil, ducts leading from said cup to the periphery of the base for conveying oil to the body of the 90 mop, and a block detachably fastened to the base and overlying a portion of the cup for securing the cup upon the base.

9. In combination, a mop having an elongated body with strands of yarn depending 95 therefrom, a base having a circular periphery, means for holding the body of the mop in contact with the circular periphery of the base, a receptacle for oil, and a duct leading from said receptacle to the strands 100 of the mop.

10. In a mop, the combination with a cloth having an annular body with strands of yarn depending therefrom, of a circular base having upstanding projections near the 105 circumference for holding the cloth expanded in circular outline, a plurality of radial projections extending from the circumference of the base for holding the strands evenly distributed, and oil ducts 110 within said base and leading to the ends of said radial projections for conveying oil to the strands of the mop.

11. In a mop, the combination with a cloth having an annular body with strands 115 of yarn depending therefrom, of a base adapted to support the cloth and hold the body thereon in circular form, a cup seating upon said base and overlying a portion of the cloth to retain the same in position, 120 and ducts leading from said cup to the circumference of the base for conveying oil to the strands of the mop.

12. In a mop, the combination with a cloth having an annular body with strands 125 of yarn depending therefrom, of a base

adapted to support the cloth and hold the body thereon in circular form, a cup seating upon said base and overlying a portion of the cloth to retain the same in position, 5 ducts leading from said cup to the circumference of the base for conveying oil to the strands of the mop, and means detachably attached to the base for holding the cup upon the base.

In witness whereof we have hereunto subscribed our names in the presence of two witnesses.
